UNITED STATES PATENT OFFICE.

JOSEPH STONE AND BEN G. PERRY, OF BESSEMER, ALABAMA.

MOLDING MACHINE.

Application filed June 1, 1922. Serial No. 565,101.

To all whom it may concern:

Be it known that we, JOSEPH STONE and BEN G. PERRY, citizens of the United States, residing at Bessemer, in the county of Jefferson and State of Alabama, have invented 5 certain new and useful Improvements in Molding Machines, of which the following is a specification, reference being had therein to the accompanying drawings.

10 This invention relates to molding machines and it has for its object the provision of a mechanism whereby sand is discharged by centrifugal force and with such velocity into the flask of a molding machine 15 as to cause the firm compacting of the sand within the flask and without any tamping upon the part of the molder.

It is a further object of the invention to 20 so associate a flask support with the centrifugal sand discharging apparatus of the character indicated as to permit of the ready withdrawal of the flask support and flask and the substitution of another flask, so that the flask may be quickly returned to position 25 to receive more sand from the centrifugal sand discharging device.

Further objects and advantages of the invention will be set forth in the detailed description which follows.

30 In the accompanying drawings:

Fig. 1 is a view partly in longitudinal section of a machine constructed in accordance with the invention;

35 Fig. 2 is a view in transverse vertical section of the machine illustrated in Fig. 1; and

Fig. 3 is a detail view of a shaker bar hereinafter described.

40 Like numerals designate corresponding parts throughout the several figures of the drawings.

45 Referring to the drawings it will be seen that this improved molding machine comprises a frame consisting of the end plates 5 which are tied together by the longitudinally extending fixed cylinders 6. The end frame members 5 are supported upon track wheels 7 and said track wheels travel upon rails 8 so that the machine as a whole 50 may be advanced toward a pile of sand to cause a conveyor 9 to pick up sand from the pile and discharge it into a sand hopper 10. The sand is discharged from the sand hopper by means of chutes 11 through the 55 sand inlet openings 12 of the fixed cylinders 6. Within these cylinders the sand is engaged by blades 13 upon rotative drums 14. These drums are caused to rotate at a high rate of speed by means of motors 15, as presently set forth and they act to 60 hurl sand with great velocity through the openings 16 formed in the lower inner sides of the fixed cylinders 6 and to discharge the said sand with great force into the flask 17 of a flask carrier 18. The shafts 19 of drums 14 carry pulleys 20 which are driven by belts 21 from the motors 15. The two drums 14 are caused to rotate in opposite directions or in the direction of the arrows A, in Fig. 1. The flask carrier 18 is provided with wheels or rollers 22 which travel upon a trackway 23 formed upon the end frame members 5, the construction being such that the carrier may be moved to the position illustrated in Fig. 1 where it lies in position to receive the sand discharged by the blades 13, or may be moved outwardly to a position where the flask 17 may be lifted from the carrier 18 and an empty flask substituted therefor, after which the carrier may be rolled back to sand receiving position. Movement of the carrier along the trackway 23 is effected by a hand wheel 24 which is mounted upon a shaft 25, 70 said shaft carrying gear wheels 26 which mesh with racks 27 of the carrier 18.

It is immaterial what particular shape of article is handled by the molding machine, since this molding machine may mold 75 articles of varying sizes and shapes without departure from the invention.

Further it is immaterial what particular means is employed to get the sand into the sand hopper. It may be delivered into this 80 hopper by hand without departure from the invention, the essential feature of the invention residing in the provision of a centrifugal discharge mechanism for hurling sand into a mold with sufficient force to 85 compact the sand therein without further tamping.

For controlling the flow of sand from the hopper we provide any desired number of shaker bars 28 which constitute the bottom 90 of the hopper. These shaker bars project through the sides of the hopper and are connected to links 29 by which they are supported. Connecting rods 30 are connected with upturned ends 31 of the shaker bars 95 and are actuated by eccentrics 32 on a shaft 100

105

110

33. This shaft may be connected at will by any conventional type of clutch 33^a, to a pulley 34 that is driven by a belt 35 or in any other way, from a part of the conveyor mechanism, the latter, in turn, being driven by a motor 38. By virtue of the provision of the clutch the movement of the shaker bars may be stopped to cause the flow of sand to cease when the flask is withdrawn from beneath the cylinder 6. The shaker bars operate with a back and forth movement and when one bar is moving in one direction adjacent bars are moving in the opposite direction. Thus the sand is fed from the hopper into the cylinders 6.

It is, therefore, to be understood that the invention is not limited to the precise construction set forth but that it includes within its purview whatever changes fairly come within either the terms or the spirit of the appended claims.

Having described our invention what we claim is:

1. In combination a wheeled frame, a pair of fixed cylinders thereon, a pair of rotative elements in said cylinders, a sand hopper above said cylinders delivering sand into said cylinders, said cylinders having

openings at their inner and lower sides, a trackway upon the frame and a flask carrier mounted upon the trackway for movement to bring it into and out of operative position with respect to said cylinders.

2. A structure as recited in claim 1 in combination with means for causing the flask carrier to travel upon the trackway including manually operable gear wheels and straight line racks with which said gear wheels mesh.

3. In combination a wheeled frame, a pair of fixed cylinders thereon, a pair of rotative elements in said cylinders, a sand hopper above said cylinders delivering sand into said cylinders, said cylinders having openings at their inner and lower sides, a trackway upon the frame extending at right angles to the axes of said cylinders and a flask carrier mounted upon the trackway for straight line movement to bring a flask carried thereby beneath said cylinders or outwardly beyond said cylinders.

In testimony whereof we hereunto affix our signatures.

JOSEPH STONE.
BEN G. PERRY.
